IRONER ROLL COVERING UNIT

John G. Schoepf, Philadelphia, Pa., assignor to
Asten-Hill Mfg. Co., Philadelphia, Pa., a corpora-
tion of Delaware

Application January 17, 1941, Serial No. 374,947

10 Claims. (Cl. 139—384)

This invention relates to ironing machines, and is directed to an improved covering for the rolls in such machines adapted to provide a yielding surface in conjunction with the heated ironing surface with which such rolls coat.

It is the usual practice to provide ironer rolls with a resilient pad of cotton fibers or other felted material, and after applying the same to surround the pad with an outer covering cloth so as to retain it in position. Coverings of this character have a limited life and the renewal thereof is a matter of inconvenience. Also, it is difficult to so apply such a covering to a roll to obtain an over-all diameter suitable for the limited space available between the periphery of the roll itself and the opposing ironing surface of the machine.

It is the primary object of the invention to overcome difficulties such as those mentioned by providing an improved form of roll covering which can be readily applied to ironer rolls, and at the same time to so form the covering that the same will have a substantially longer life, and retain its desired resilient padding properties.

The proposed new covering includes a pad section and an outer covering section combined in a single unit, and normally being integrally constituted.

The pad section of the covering unit will be formed as a woven fabric structure, the thickness of which is adjusted to appropriate dimensions by proper selection of the size of the threads and the number of woven plies therein. To provide the requisite resiliency of the pad section, relatively thick threads are employed therein which involves a relatively coarse weave.

The outer covering section which will constitute a prolongation of the pad section will comprise woven fabric of sufficiently fine weave as to provide a relatively smooth surface thereon suitable for contact with the goods being ironed, and for this reason the same will be of finer weave, and incorporate finer threads, than the pad section. Where, as is preferable, the two parts of the covering are to be formed as an integral unit, the same warp threads may extend throughout both sections. The outer covering section will be of lesser thickness than the pad section, and this is accomplished through the use of finer weft threads, and the weaving thereof with a lesser number of plies, than the pad section.

To render the proposed covering unit durable, and capable of withstanding the combined de-

teriorating effects of heat and moisture to which the same is necessarily subjected in an ironing machine, it is proposed to use asbestos material in both pad section and the covering section.

5 In particular, it is proposed to form the pad section as a woven asbestos fabric, and to form the outer covering section as a woven asbestos fabric, and these are desirably constituted as an integrally woven unit according to the features previously mentioned.

In addition to the pad section and the outer covering section, it is desirable, although not entirely necessary, to incorporate an anchoring strip as a prolongation of the inner end of the 15 pad section adapted to be appropriately secured to the surface of an ironer roll. The anchoring section is preferably formed integrally with the other sections, and like the covering section, will have different characteristics from the pad section.

20 The invention will be understood by reference to the illustrative embodiment thereof shown in the accompanying drawing and the following detailed description.

25 In such drawing:

Fig. 1 is a perspective view of an ironer roll covering unit according to the invention.

Fig. 2 is an end view of an ironer roll with the covering unit applied; and

30 Fig. 3 is a more or less diagrammatic view greatly enlarged illustrating certain points of the unit shown in Figure 1.

The covering unit includes an anchoring strip 10, a pad section 11 and an outer covering section 12 terminating in an outer end 13. Such parts are all joined to form a unitary structure. It will be observed that the pad section 11, in order to provide the desired resiliency, is substantially thicker than the other parts. The

35 same is comprised of woven fabric so as to provide a substantially more durable structure than the felted pads ordinarily used heretofore. The outer covering section 12 is thinner than the pad section 11 and will be of finer weave to provide a sufficiently smooth surface to be suitable to contact the work being ironed. The form and character of the anchoring section 10 is of no particular consequence, and in some embodiments of the invention may be entirely omitted.

45 Where employed it will, like section 12, be thinner than pad section 11, and as a matter of convenience may be of the same character as section 12.

To secure an integral structure devoid of any 50 lapped or other seamed joints which would be

objectionable in the intended usage of the unit, the various sections are woven as a single unit, and the variation in thickness of the sections obtained through the employment of different numbers of plies and threads of different thickness. The integral character of the various sections is obtained by using common warp threads extending through the various sections in a direction lengthwise of the unit. These various points will be understood by reference to Figure 3. As is therein shown the warp threads *a* extend through the anchor section 10, the pad section 11, and outer covering section 12. The weft threads *b* in section 10 are of relatively small size. In pad section 11, weft threads *c* of considerably larger size are employed, the same being relatively soft and thick to give the pad section suitable resiliency. Further, it will be noted that three integrally woven plies are provided in section 11 through the use of three series of the weft threads *c*. The various warp threads *a* are suitably interwoven with the weft threads constituting the different plies through the employment of any suitable multiply weave such as known to the art, it being understood in this connection that the weave shown in Figure 3 is merely illustrative.

The outer covering section 12 will be formed of substantially less thickness than the pad section 11 by utilizing a lesser number of plies therein and also employing smaller weft threads *d*. The weft threads in the covering section may be of the same character as weft threads *b* in the anchoring section 10 although this is not essential. To provide a smooth surface in the outer covering section 12, it is desirable that weft threads *d* and the warp threads *a* which extend throughout the different sections be of more or less the same size.

Both sections 12 and 10 will ordinarily comprise single ply woven fabric, but in any event as above indicated will be so formed as to be substantially thinner than pad section 11, it being understood that the resiliency of the covering unit is intended to be obtained through pad section 11 by reason of the thickness and character of the threads employed in such section.

The one piece covering unit of the invention is shown applied to an ironer roll 18 in Figure 2. Anchor section 10 is secured to the periphery of the roll through a suitable heat and moisture resisting adhesive, or through any other suitable securing means. Such section need be only a few inches long and extend only a short distance around the periphery of the ironer roll 18, it being unnecessary to use an anchoring section making a plurality of turns around the roll. The pad section 11 is preferably made of a length so as to extend once around the roll to bring the opposite ends of said section into substantially abutting relation as shown in Figure 2, and the outer covering section 12 is preferably made of a length slightly greater than the circumference of the roll so as to make one complete convolution therearound and allow the end portion thereof adjacent the extremity 13 to overlie and extend somewhat beyond the line of abutment of the opposite ends of pad section 11. With such arrangement the over-all diameter will be determined primarily by the thickness of the pad section 11, which as before mentioned will be initially formed to an appropriate thickness through proper selection of the size of the weft threads and number of plies therein. Practical experience indicates that with standard size ironer

rolls of between 11 and 12 inches in diameter, best results are secured by using three plies in such section as above described. It will be evident, however, that substantially the same thickness can be secured by employing two plies with the substitution of weft threads of larger size.

It will be further understood that while preferably the lengths of the pad and outer covering sections 11 and 12 will each be such as to make one convolution around the ironer roll, either or both of such sections may be made of such length as to make a plurality of convolutions about the roll. In the latter instance, it may be found desirable to form pad section 11 with a lesser number of plies and/or with smaller weft threads in order to avoid excessive over-all diameter of the unit in its position on the roll, inasmuch as the distance between the periphery of the roll itself and the coacting ironing surface of the machine is ordinarily only $\frac{1}{2}$ of an inch.

The weft threads *c* and *d* of sections 11 and 12 may comprise any suitable material, but preferably will be asbestos threads, inasmuch as asbestos is particularly suitable to withstand the adverse effects of heat and moisture to which the covering unit is exposed in the ironing machine. Warp threads *a*, which extend through the different sections, may comprise any suitable materials, particularly inasmuch as there is comparatively little tensile strain lengthwise of the covering unit. However, it is normally preferred to insure against deterioration that such warp threads as well as the weft threads of the different sections shall be constituted of some form of asbestos threads.

I claim:

1. An ironer roll covering unit consisting essentially of a multiply woven fabric pad section adapted to be wrapped around the roll, and a single ply, thinner fabric outer cover section woven with smaller weft threads than the weft threads in the pad section and woven end to end as a unit with the pad section with common warp threads extending continuously throughout the length of the unit.

2. An ironer roll covering unit consisting essentially of a woven fabric pad section adapted to extend about the roll and a thinner outer cover section adapted to surround the pad section integrally woven with common warp threads extending continuously from the one to the other section, and asbestos weft threads in both sections, the pad section being substantially thicker than the cover section and the asbestos weft threads in the pad section being substantially heavier than the asbestos weft of the outer cover section.

3. An ironer roll covering unit consisting essentially of a multiply woven pad section adapted to extend about the roll woven with relatively heavy asbestos weft threads, and a relatively thin outer cover section, adapted to surround the pad section woven with substantially lighter asbestos weft threads than the pad section and being woven end to end with the pad section with common asbestos warp threads extending continuously throughout the length of the unit.

4. An ironer roll covering unit consisting essentially of a thin anchoring strip section for securing the unit to the roll, a pad section adapted to extend about the roll, and a thin outer cover section adapted to surround the pad section, said three sections being arranged end to end, one after another, and being composed as an integral woven fabric unit having common warp

threads extending continuously throughout the length thereof wherein the pad section is of substantially thicker weave and more compressible than each of the other sections.

5. An ironer roll one-piece covering unit consisting essentially of a relatively thick woven fabric pad section of a length almost equal to the circumference of the roll so that its ends substantially abut when the section is extended about the roll, and a substantially thinner and relatively incompressible woven fabric outer cover section integral with one end of the pad section and of a length greater than the circumference of the roll so as to overlie the abutting ends of the pad section, and a short woven fabric anchor strip section substantially thinner than the pad section adapted to anchor the unit to the roll, said anchor strip being of a length substantially less than the circumference of the roll and being woven integrally with the inner end of the pad section the sections being woven with common warp threads extending lengthwise through the length of the unit, the thick woven pad section being multiply fabric, and the end sections being single ply fabric.

6. An ironer roll integrally woven one-piece covering unit consisting essentially of a woven fabric pad section adapted to be wrapped around the roll, and a woven fabric outer cover section adapted to surround the pad section, said pad and cover sections being woven end to end with common warp threads extending continuously throughout the length of the unit, the pad section being several times the thickness of the outer cover section.

7. An ironer roll covering unit consisting essentially of an integrally woven fabric strip having lengthwise extending warp threads and crosswise extending weft threads, said strip including a section formed with relatively heavy weft threads providing a compressible relatively thick pad adapted to extend around the roll and an adjoining section composed with the same warp threads as the pad section and incorporating

substantially lighter weft threads than the pad section providing a relatively incompressible and thin outer cover adapted to surround the outer side of the pad section.

5 8. An ironer roll one-piece covering unit consisting essentially of a relatively thick and compressible multiply woven fabric pad section adapted to extend about the roll and a substantially thinner single ply outer cover section adapted to surround the pad section woven end to end with common warp threads extending continuously throughout the length of the unit.

10 9. An ironer roll one-piece covering unit consisting essentially of a relatively thick multiply woven fabric pad section adapted to extend around the roll woven with relatively heavy weft threads and an outer cover section substantially thinner than the pad section adapted to surround the pad section, said cover section being woven with lighter weft threads than the pad section and being woven end to end with the pad section with common warp threads extending continuously from the one to the other section.

15 10. An ironer roll one-piece covering unit consisting essentially of a relatively thick and compressible woven fabric pad section comprising integrally woven multiple plies of a length almost equal to the circumference of the roll so that its ends are adapted to substantially abut when the section is extended about the roll, an anchor strip section of shorter length than the circumference of the roll and of substantially thinner weave adapted to anchor the unit to the roll extending from one end of the pad section and adapted to underlie the opposite end of the pad section when in position on the roll, and a cover section of substantially thinner weave than the pad section extending from the second end of the pad section, said cover section being of a greater length than the circumference of the roll so as to overlie the abutting ends of the pad section.

JOHN G. SCHOEPPF.
